Primary Examiner—Louis S. Zarfas*Assistant Examiner*—Monica A. Weingart*Attorney, Agent, or Firm*—William B Ritchie[57] **CLAIM**

The ornamental design for the adjustable bullet foot insert, as shown and described.

DESCRIPTION

FIG. 1 is an isometric view of the first embodiment of the adjustable bullet foot insert in accordance with the invention.

FIG. 2 is a side view of the embodiment of FIG. 1 showing the foot fully extended.

FIG. 3 is a side view of the embodiment of FIG. 1 showing the foot fully retracted.

FIG. 4 is a bottom view of the embodiment of FIG. 1.

FIG. 5 is a top view of the embodiment of FIG. 1.

FIG. 6 is an isometric view of a second alternative embodiment of the adjustable bullet foot insert in accordance with the invention.

FIG. 7 is a side view of the embodiment of FIG. 6 showing the foot fully extended.

FIG. 8 is a side view of the embodiment of FIG. 6 showing the foot fully retracted.

FIG. 9 is a bottom view of the embodiment of FIG. 6.

FIG. 10 is a top view of the embodiment of FIG. 6.

FIG. 11 is an isometric view of a third alternative embodiment of the adjustable bullet foot insert in accordance with the invention.

FIG. 12 is a side view of the embodiment of FIG. 11 showing the foot fully extended.

FIG. 13 is a side view of the embodiment of FIG. 11 showing the foot fully retracted.

FIG. 14 is a bottom view of the embodiment of FIG. 11.

FIG. 15 is a top view of the embodiment of FIG. 11.

FIG. 16 is an isometric view of a fourth alternative embodiment of the adjustable bullet foot insert in accordance with the invention.

FIG. 17 is a side view of the embodiment of FIG. 16 showing the foot fully extended.

FIG. 18 is a side view of the embodiment of FIG. 16 showing the foot fully retracted.

FIG. 19 is a bottom view of the embodiment of FIG. 16.

FIG. 20 is a top view of the embodiment of FIG. 16.

FIG. 21 is an isometric view of the preferred embodiment of the adjustable bullet foot insert in accordance with the invention.

FIG. 22 is a side view of the embodiment of FIG. 21 showing the foot fully extended.

FIG. 23 is a side view of the embodiment of FIG. 21 showing the foot fully retracted.

FIG. 24 is a bottom view of the embodiment of FIG. 21; and, FIG. 25 is a top view of the embodiment of FIG. 21.
